FLOWER POT

Dirk Laan, P.O. Spoorsingel 38,
Bovenkarspel, Netherlands

Filed Sept. 5, 1961, Ser. No. 66,598

Term of patent 14 years

(Cl. D35—3)

FIG. 1

FIG. 3

FIG. 4

The side of the flower pot which is not shown is like the side which is shown in FIG. 1.

The characteristic features of my design for a flower pot reside in the specific holder in association with the bowl, as shown.

I claim:

The ornamental design for a flower pot, as shown and described.
